UNITED STATES PATENT OFFICE.

JAMES F. HARRISON, OF CHATTANOOGA, TENNESSEE, ASSIGNOR TO CHATTANOOGA BOTTLE & GLASS MANUFACTURING COMPANY, OF CHATTANOOGA, TENNESSEE, A CORPORATION OF TENNESSEE.

DESIGN FOR A BOTTLE.

Application filed May 18, 1927. Serial No. 22,084. Term of patent 14 years.

To all whom it may concern:

Be it known that I, JAMES F. HARRISON, a citizen of the United States, residing at Chattanooga, in the county of Hamilton and State of Tennessee, have invented a new, original, and ornamental Design for Bottles, of which the following is a specification, reference being had to the accompanying drawing, forming part thereof.

The figure is a side view of a bottle, showing my new design.

I claim:

The ornamental design for a bottle, as shown.

JAMES F. HARRISON.
